INCANDESCENT ELECTRIC LAMP

Ralph B. Thomas, Beverly, Mass., assignor to
Hygrade Sylvania Corporation, Salem, Mass., a
corporation of Massachusetts

Application November 7, 1938, Serial No. 239,243

10 Claims. (Cl. 176—32)

This invention relates to incandescent electric lamps, and particularly to such lamps of the bipost type, gas-filled.

When the filament of such a lamp burns out, an electric arc occurs across the break in the filament, and may eventually transfer itself to an arc across the filament leads. This arc will draw a much larger current than did the filament, and will rapidly heat and expand the gas in the bulb, often with explosive violence, bursting the bulb and scattering the fragments, creating a hazard to the persons and property in the vicinity.

The destructive arcing described can be prevented by incorporating within the lamp structure a fuse which will blow before the lamp current rises to the destructive value. The fuse must be positive in action, and should be placed outside of the sealed glass bulb of the lamp.

Accordingly, one of the objects of the present invention is to incorporate in such a lamp a fuse which will be positive in its action toward preventing destructive arcs.

A further object of the invention is to provide such a fuse in the outwardly extending contact prong at the base of the lamp.

Another object is to provide proper arc-quenching insulation for the fuse and yet keep the prong an integral unit.

Further objects and advantages will be apparent from the following description and the accompanying drawing in which:

Figure 1 is a profile view of the finished bipost lamp, and

Figure 2 is an enlarged view, in cross-section, of the fuse and prong of the lamp.

Figure 1 shows a lamp in a glass bulb 1, preferably of "Pyrex" or hard glass. The filament 2, generally arranged in a plane, is supported from the wire leads 3, 3, the insulating pieces 4, 4, preferably of ceramic or refractory material, and the hooks 11. A metal gauze piece 5, may be attached to each lead to collect particles of tungsten evaporated from the filament 2 and carried upward by convection currents in the gas, but the same piece cannot be connected to both leads as it will cause a short circuit. The leads are rigidly attached to the base prongs 7, 7, the whole forming a rigid assembly. The base prongs are preferably surrounded by the thin metal cups 8, 8, of a metal, such as "Fernico", which is capable of being sealed to the glass used. A bushing, or sealing ring of copper 9, 9, is generally used between the prong 7, and the cup 8, the bushing being generally formed by a brazing

process. The fuse is contained in the prong 7, and is shown in more detail in Figure 2. Preferably, as shown, only one prong has a fuse.

In the latter figure, the metal prong 7, to which the lead 3, is attached, extends in the form of a hollow shaft 12, beyond the cup 8. The fuse wire 10, is electrically connected, as by solder 6, to the bottom of this hollow shaft, and extends such distance as is required. An insulating tube 14, which may be conveniently made of glass, is placed around the fuse 10, to insulate it from the hollow shaft of the prong. An insulating material of ceramic 15, or similar material having a slight shoulder on one end, is placed around the outer surface of the hollow shaft 12, and a metal sleeve 16, is placed over it to provide an outer contact for the lamp and to partially close the open end of the metal prong, as by the sleeve's being mounted inward at its end. A reasonable distance, for example $\frac{1}{16}$ inch, should be allowed between the end of the prong and the lower end of the metal sleeve 16; this distance may be fixed by the dimensions of the shoulder of the ceramic insulator 15. The top of the fuse 10, is connected by a heavy wire 19, of larger diameter than the fuse wire and of copper or other material of good conductivity to the top of the metal sleeve 16, and the opening at the sleeve is closed by a plug, 17, of cement 18, which also serves to hold the sleeve and the prong together. This cement may extend down as far as the fuse 10, if desired.

The cement 18, used in the plug 17, may consist of zirconium silicate of about 150 mesh mixed with enough sodium silicate to form a fairly dry paste which will not flow readily, but which may be pushed into the top of the metal sleeve 16. The cement may be set preferably by heating to a temperature of about 100° C., and will then be somewhat porous, allowing the gases formed by the fuse burnout to diffuse through it. Other suitable cements may, of course, be used if desired.

I have found a wire consisting of nickel, or of a nickel alloy such as nickel and manganese, to be suitable for the fuse wire 10, although other wires may also be used.

The cup 8, of metal, sealed to the glass of the lamp envelope may be of "Fernico" metal if the glass envelope is made of a "hard" or high melting point borosilicate glass, such as that commonly known as Pyrex glass. "Fernico" consists of 54% iron, 28% nickel, and 18% cobalt.

The impossibility of properly protecting the lamp against arcing at burnout has prevented

the filling of prior art lamps of the type described, with gases such as pure argon, or 98% pure argon. Such a pure-argon filled lamp would have arced at burnout.

5. When the lamp filament 2, burns out an arc is established between the leads 3, 3, within the bulb 1, the current through the fuse 10, increases and the fuse "blows". The glass insulating tube 14, restricts the diameter of the resultant arc 10 across the blown ends of the fuse 10, and prevents the arc jumping from the live contact to the inside of the hollow shaft 15. The heavy copper wire 14, insures that the arc to the fuse 10, does not travel beyond the limits of the fuse 15 wire itself. If the fuse wire itself were continued in sufficient length to make contact with the external terminal, the fuse might blow at the outer surface or socket contact of the metal sleeve 13, and cause an arc which would continue 20 across the socket contacts which are closely spaced at the base. The arc at fuse burnout is confined to the space inside the cemented seal. This cement being porous, temporarily confines the gases resulting from the vaporization of the 25 fuse material, thereby permitting an abnormal pressure to result which acts to assist in quenching the fuse arc and subsequently permits a retarded diffusion of these gases with resulting slow return to normal pressure within the fuse 30 chamber.

What I claim is:

1. In a lamp of the character described, a base contact prong containing an internal fuse to prevent destructive arcing at burnout of the lamp.
2. In a gas-filled electric incandescent lamp, a glass envelope, a filament supported by rigid leads attached to external contact prongs sealed through said glass envelope and extending outwardly therefrom, said contact prong containing an internal fuse to prevent destructive arcing at burnout of the lamp.
3. In a lamp of the character described, a base contact prong containing an internal fuse therein, said fuse comprising a fuse wire electrically connected to the bottom of said prong, and an insulating tube enclosing said fuse wire inside of said prong.
4. In a lamp of the character described, a base contact prong bearing an internal fuse, said fuse comprising a fuse wire electrically connected to bottom of said prong, an insulating tube enclosing said fuse wire inside of said prong and a heavy conductive wire connected to the fuse wire and to an external sleeve insulated from said prong.
5. In a lamp of the character described, a base contact prong containing an internal fuse, said fuse comprising a fuse wire electrically connected to bottom of said prong, an insulating tube enclosing said fuse wire inside of said prong, a wire of larger diameter than the fuse wire and of more conductive material, connected to said fuse wire and to an external sleeve insulated from said prong, and a porous insulating cement sealing the fuse cavity of the prong.

6. In a lamp of the character described, a base contact prong containing an internal fuse, said fuse comprising a fuse wire electrically connected to bottom of said prong, an insulating tube enclosing said fuse wire inside of said prong, a wire of larger diameter than the fuse wire and of more conductive material, connected to said fuse wire and to an external sleeve insulated from said prong, a porous insulating cement sealing the fuse cavity of the prong, an insulating material placed around the outer surface of said prong and a metal sleeve enclosing said insulating material and sealed to said non-fusing conductive wire by said cement.

7. In a lamp of the character described, a base contact prong containing an internal fuse, said fuse comprising a fuse wire electrically connected to bottom of said prong, an insulating tube enclosing said fuse wire inside of said prong, a wire of larger diameter than the fuse wire and of more conductive material connected to said fuse wire and to an external sleeve insulated from said prong, an insulating porous cement sealing the fuse cavity of said prong, an insulating material placed around the outer surface of said prong containing a shoulder one-sixteenth of an inch or greater at one end, said shoulder separating the metal of the outer sleeve from the protruded lip of said prong, and a metal sleeve reentrant on one end enclosing said insulating material and sealed to said non-fusing conductive wire by said semi-porous cement.

8. In an electric incandescent lamp, a glass envelope, a filament supported by two rigid leads attached to external contact prongs sealed to the glass envelope and extending outwardly therefrom, said contact prong comprising a metal extension in the form of a hollow shaft, a fuse wire inside said hollow shaft and electrically connected to the bottom thereof, an insulating tube enclosing said fuse wire and inside said shaft, a wire of larger diameter than the fuse wire and of more conductive material, and attached to end of the fuse not connected to bottom of said shaft, an insulating material around the outer surface of said hollow shaft, a metal sleeve over said insulating material and out of contact with said hollow shaft, and a quantity of cement closing the open end of the metal sleeve, and binding the sleeve and insulating material to the hollow shaft.

9. The combination of claim 8 in which the wire of more conductive material than the fuse wire and attached to the end of the fuse wire is of copper.

10. In a lamp of the character described, a sealed glass envelope, a tungsten filament within said envelope, and connected to base prongs sealed through and extending outwardly from said envelope, a fuse inside one of said base prongs, and an atmosphere consisting of at least 98 per cent pure argon inside said envelope.

RALPH B. THOMAS.
